UNITED STATES PATENT OFFICE.

ARTHUR JULES FRANCOIS JOSEPH COUSIN, OF JEMEPEPE-SUR-MEUSE, BELGIUM, AS
SIGNOR TO SOCIÉTÉ ANONYME JOHN COCKERILL, OF SERAING, BELGIUM, A COMPANY OF BELGIUM.

FURNACE FOR THE DIRECT REDUCTION OF METALLIC ORES.

Application filed March 14, 1923. Serial No. 624,946.

To all whom it may concern:

Be it known that I, ARTHUR JULES FRANCOIS JOSEPH COUSIN, a subject of the King of the Belgians, residing at Jemeppe-sur-Meuse, in the Kingdom of Belgium, have invented certain new and useful Improvements in Furnaces for the Direct Reduction of Metallic Ores, of which the following is a specification.

10 This invention relates to a furnace adapted to be used in different industrial operations, principally for the direct production of iron starting from its ores, but suitable also for the calcination, roasting or sintering of other ores, the manufacture of lime, the burning of bricks, of clinker in order to obtain cement, the agglomeration of powdered ores with or without previous briquetting, and finally all operations based 20 on the heating of materials which should not retain a high temperature when issuing from the furnace.

The improved furnace has, in its general construction, all the arrangements common 25 to furnaces of the type known as "tunnel furnaces" and the hearth is formed by platforms connected end to end and carried on a train of trucks. It is distinguished however essentially from other furnaces of the 30 same type by the fact that it is divided along its length by means of dampers into different zones or chambers, thus providing in one and the same furnace, chambers each producing separate reactions and independent 35 of each other without reciprocal action being able to interfere with the final result.

In carrying out the invention practically the furnace is provided with one or more burners or lines of burners, which burn 40 under pressure, arranged in the arch of the furnace and controlled in different ways so as to produce for example in a certain zone an oxidizing or neutral flame and in another zone a reducing effect.

45 In the case where the reduction is effected by a reducing gas passing through the material to be treated, the platforms of the trucks forming the hearth of the furnace are made double and leave between them an empty space of a certain height which is closed in at the sides by the walls of the furnace in such a way as to furnish a passage for the gases which pass through under the draft of the chimney, after hav-

ing traversed the mass of material in a 55 powdered or fragmentary state carried by the upper platforms or boxes with perforated bottoms.

In the accompanying drawings:

Figures 1 and 2 represent a longitudinal 60 section of the furnace, the part thereof shown in Figure 2 forming a continuation of the part shown in Figure 1 and connected at the line A—A.

Figure 3 is a transverse section.

The furnace shown is intended to be heated by gas, either producer gas of low quality, blast furnace gas or gas from coke ovens although powdered coal or oil may be used. It is constituted by a conduit 1 70 of masonry forming a tunnel in which a train of trucks 2, (drawn along by a chain or any other equivalent traction device not shown) traveling along a track 3, runs through the furnace and presents in succession each of its elements (or trucks 2) to the action of the burners 4. These burners 4 as shown are simply iron pipes set in the arch or crown of the furnace. The air to support combustion is supplied to them by 80 a blower 5 which communicates a certain pressure to them for example about 10 centimetres of water. In consequence of this pressure and the narrow section of the gas conduits the current of air and gas acquires 85 a considerable velocity which shifts forward the point of combustion some distance in front of the gas outlets.

It follows therefore that the gas conduits are sufficiently cooled by the passage of the cold fuel and the air, the maximum temperature of which is 350° C. and that therefore all cooling by means of water can be dispensed with. The position also of the burners in the arch or crown of the furnace 90 removes them from the flame and contributes towards keeping them at a comparatively low temperature. The burners direct their flames obliquely in a downward direction 95 on to the surface of the material to be treated.

The furnace is provided at the truck inlet end with a door 6 and at the truck outlet end with a damper 7 through the adjustable opening 8 of which the air to support combustion enters. After having passed directly through the furnace for a certain distance in the direction of the arrows 9 the

air is drawn into the conduit 10 by the blower 5 which forces it to the burners through the conduit 11.

The trucks 2 have, in the example shown 5 a lower platform 12 provided with longitudinally extending flanges 13 (see Figure 3) which project downwards and dip into gutters 14 filled with water. The hydraulic seal thus constituted protects the lower part 10 of the furnace containing the devices on which the trucks travel from the action of the flames or the hot gases. Each platform 12 carries on supports 15 an upper platform 16 in the form of a box with a perforated bottom 15 adapted to receive the material to be treated which in this case is in a powdered or fragmentary state. The result is that the gases of combustion pass through the powdered material to be treated as shown by 20 the arrows 17, then through the perforations in the bottoms of the boxes 16 and then into the space 18 between the two series of platforms 12 and 16 and finally escape by the chimney 19.

25 The furnace is divided along its length into different zones or chambers each having their own special function.

The first zone 20 comprised between the door 6 for the entrance of the trucks 2 and 30 the combustion chamber 21 (which may be of the multiple type shown in the drawing) is the zone of preparation. It is into this zone that the flue 19 leading to the chimney opens.

35 The second zone called the zone of combustion or reaction, is composed of one or more chambers 21 into which the burners 4 penetrate, the flames from which are projected directly onto the material to be treated.

40 A third zone or zone of cooling completes the furnace. This zone extends between the last combustion chamber 21 and the damper 7 and is divided into two sections 22 and 23 45 by dampers 24 and 25 the function of which is to isolate the section 22 thus cutting it off from the action of the blower 5.

In the normal operation the train of trucks 2 connected to each other occupies the whole 50 length of the furnace. The thrust which causes one truck to enter the furnace causes another to emerge from the opposite end thereof. The furnace therefore always contains the same number of trucks. A damper 55 26, placed in the zone of preparation 20 is adjusted in such a way as to always be as near as possible to the train of trucks and yet leave sufficient draught to prevent the creation of any pressure in the combustion 60 zone 21, but at the same time avoiding any reduction of pressure below atmospheric pressure. The function of this damper 26 is therefore to maintain as much as possible a null pressure in the combustion 65 chamber 21. Under these conditions it is

possible to maintain in one and the same furnace oxidizing and reducing chambers without the two reactions interfering with each other.

The material carried by the trucks therefore becomes gradually heated up by contact with the burnt gases which are inert and still hot which fill the zone of preparation 20, and the material already at a high temperature is passed into the combustion chamber 21.

70 According to the nature of the operations to be effected the first burner 4 or the first line of burners 4 can be regulated by acting on the regulating cocks or valves so as to give an oxidizing or a neutral flame. Afterwards, as the trucks continue to advance, the material is exposed to the second burner 4 (or line of burners) regulated for example so as to obtain a reducing effect by causing 80 the fuel employed (e. g., gas, oil or powdered coal) to be supplied with a supply of air to support combustion reduced to a minimum.

85 In the cooling zone 22, the material while still hot is in a neutral atmosphere, without any appreciable pressure and is subjected to the reaction of the materials in contact e. g., metallic oxides and carbon, which reaction takes place in consequence of the elevation of the temperature. This reaction in 90 the case of iron oxide is endothermic and causes rapid cooling down to a temperature at which no reaction can take place. At this moment the material may be passed into the second zone of cooling 23 where it gives 95 up the remainder of its heat to the air to support combustion and which circulates in the direction of the arrows 9, that is to say, in the reverse direction to that in which the material travels. This latter when completely treated emerges finally through the 100 door 7.

105 The separation of the cooling zone into two sections 22 and 23 is for the purpose of preventing certain disadvantages the chief one of which is the drawing in of flames or burnt gases by the blower 5 with as a consequence the blowing into the combustion chamber 21 of air laden with carbon dioxide; on the other hand in the case of a reduction 110 of pressure below atmospheric pressure in the combustion chamber 21 the air could be drawn in too great volume which might cause cooling of the flame and a general disturbance in the working of the furnace.

115 These accidents cannot occur as long as the pressure in section 23 of the cooling zone remains null or thereabouts. This is obtained by the working of the two dampers 24 and 25 between which there is an opening 27 120 pierced in the arch or crown of the furnace.

125 The two dampers 24 and 25 are always lowered as much as possible so as to just touch the surface of the trucks as they pass through. The closing thus obtained is not 130

however hermetic and the air can in case there is any pressure formed in the chamber 22 escape through the opening 27 thus bringing back the pressure to the limits within which its effect is not harmful. The zone 22 is therefore a zone in which the same atmosphere can be maintained as in the combustion chamber.

In practice the door 7 through which the trucks emerge is provided with a wicket (not shown) which acts as a damper and serves to regulate the size of the opening 8. This door may occupy the positions I and II, position I corresponding to the closed position. In the raised position II of this door the air enters through the space comprised between the platforms 12 and 16 of the trucks, and to reach the blower passes through the material to be treated.

The invention is obviously not limited to the details of construction of the furnace and of the trucks as above described. Thus for example the trucks having double platforms might be replaced by trucks having single platforms if the material to be treated (a moist mixture of oxides and carbon for example) were made up in an agglomerated form, the reduction not being affected by the passage of a gaseous reducing agent through the material but by intimate contact with the solid reducing agent. In this case use is made of a single combustion chamber 21, the production of a reducing gas being not required. In the example shown the burners 4 each have an air supply pipe 28 and a supply pipe 29 for gas or other fuel. Each pipe is provided with a regulating valve 30 which allows the combustion to be conducted at will under the conditions desired.

What I claim is:

1. In a furnace of the kind described, a tunnel, a movable hearth, means whereby the said hearth is run continuously through the tunnel, a door closing the entrance of the tunnel above the movable hearth, a damper extending transversally above the movable hearth, a preparation zone comprised between the said door and damper, a pair of dampers extending transversally above the movable hearth, combustion zones comprised between the first damper and the said pair

of dampers, each of the said combustion zones comprising inclined burners, whereby the flames of the said burners are projected directly towards the surface of the movable hearth, a damper closing the tunnel above the movable hearth, a cooling zone comprised between the pair of dampers and the closing damper, and a blower drawing air from the said cooling zone and forcing said air to the burners.

2. In a furnace of the kind described, a tunnel, a movable hearth, means whereby the said hearth is run continuously through the tunnel, dampers arranged transversally in the said tunnel above the movable hearth, whereby the tunnel is divided into a preparation zone, combustion zones, reduction zones and a cooling zone, burners arranged in the combustion and reduction zones, a pair of dampers separating the cooling zone into two sections and an opening in the roof of the furnace between the said pair of dampers whereby a pressure only slightly above that of the atmosphere is maintained in the combustion chamber and the first section of the cooling zone.

3. In a furnace of the kind described, a tunnel, trucks circulating continuously in the said tunnel, the said trucks having a lower platform and an upper platform, the lower platform being provided with longitudinally extending flanges, water-gutters in which the said flanges are dipped, whereby a hydraulic seal is formed, perforated bottoms forming part of the upper platform of the trucks, dampers arranged transversally in the tunnel above the upper-platforms of the trucks whereby the tunnel is divided into a preparation zone, a combustion zone, a reduction zone and a cooling zone, burners arranged in the combustion and reduction zones, the said burners being inclined towards the perforated bottoms of the upper platforms of the trucks and a blower drawing air from the cooling zone and forcing said air to the burners.

In testimony whereof I have affixed my signature in presence of two witnesses.

ARTHUR JULES FRANCOIS JOSEPH COUSIN.
